UNITED STATES PATENT OFFICE.

ROBERT F. METCALFE, OF ERIE, PENNSYLVANIA, ASSIGNOR, BY MESNE ASSIGNMENTS,
TO SOCONY BURNER CORPORATION, OF WILMINGTON, DELAWARE, A CORPORATION
OF DELAWARE.

ATOMIZER.

Application filed August 30, 1922. Serial No. 585,218.

To all whom it may concern:

Be it known that I, ROBERT F. METCALFE, a citizen of the United States, residing at Erie, in the county of Erie and State of Pennsylvania, have invented new and useful Improvements in Atomizers, of which the following is a specification.

This invention is designed to simplify and improve the construction of devices for atomizing fuel, particularly for fuel burners.

The invention is illustrated in the accompanying drawings as follows:

Fig. 1 shows a central section of the atomizer.

Fig. 2 a section on the line 2—2 in Fig. 1. 1 marks the combustion chamber, 2 the ignition cone, 3 the spark plug, and 4 a mounting carrying the cone 2 and the atomizer. The mounting forms the rear of the burner and has a passage 5 leading from a fuel supply pipe 7 and a passage 6 leading from an air supply pipe 8. The mounting has a screw-threaded opening 9 extending through it in which the mixture nozzle 10 is screwed, the mixture nozzle having a contracted or Venturi-shaped opening 11 at its discharge end. The nozzle has a chamber 12 leading to the contracted portion 11 and radial openings 13 lead from the chamber 12 into an annular groove 14, the annular groove being so positioned on the nozzle that it is brought into register with the passage 5 as the nozzle is screwed into the screw-threaded opening 9. A fuel jet nozzle 15 has a jet opening 16 concentric with the contracted opening 11 and so positioned in the chamber 12 as to draw in fuel and atomize the same through the mixture opening. The rear end of the nozzle is of a size to close the end of the chamber 12 and is provided with a shoulder 17 which is engaged by the end of the mixture nozzle 10. A plug 18 has an opening 19 adapted to fit over the end of the fuel nozzle 15. A packing 20 is arranged between the end of the plug 18 and the rear of the shoulder 17, the rear of this shoulder being tapered and the end of the plug being tapered so as to expand the packing in the screw-threaded opening and form a complete closure at this point.

The plug has radial openings 22 leading from the opening 19 and these openings lead into an annular groove 23 which groove registers with the passage 16. It will readily be

seen, therefore, that regardless of how the 55 plug 18 may be turned air passes from the passage 6 into the annular groove 23 through the radial openings into the opening 19 and from this through the nozzle 15 to the jet.

In order to prevent any material entering 60 the jet I provide a screen 24 over the end of the nozzle 15 and this is held in position by a spring 25 arranged in the opening 19.

The nozzle 10 is provided with a head 65 and a gasket 26 is arranged under this head to assure a tight joint against the leakage of fuel from the passage 5. The plug 18 also has a head and a gasket 27 is arranged under this head so as to complete the closure at the end of the plug against leakage of air from 70 the passage 6.

In the operation of the device air under pressure is delivered through the passage 6, passes through the annular chamber 23 and passages 22 to the opening 19. The air 75 passes from this through the nozzle 15 discharging at the jet 16 and aspirates the fuel moving from the fuel passage 5 through the annular passage 14, radial openings 13 to the opening or chamber 12. The jet not only 80 aspirates the fuel passing through the mixture nozzle 10 but sprays the mixture from the Venturi-shaped opening 11 at the discharge end of the nozzle. The rich mixture 85 thus delivered is ignited by the spark plug 3.

What I claim as new is:

1. In an atomizer, the combination of a mounting, having a screw-threaded opening therethrough; a mixture jet nozzle screwed into the opening having a chamber at its 90 rear with a fuel connection; an air nozzle extending into the chamber; and a plug screwed into the rear of the mounting and having an air connection and forming a joint with the air nozzle.

2. In an atomizer, the combination of a mounting having a screw-threaded opening therethrough; a mixture jet nozzle screwed into the opening having a chamber at its rear with a fuel connection; an air nozzle extending into the chamber; and a plug 100 screwed into the rear of the mounting and having an opening receiving the air nozzle and forming a joint therewith, said plug having an air connection leading to the 105 nozzle.

3. In an atomizer, the combination of a mounting having a screw-threaded opening

therethrough; a mixture jet nozzle screwed into the opening having a chamber at its rear with a fuel connection; an air nozzle extending into the chamber; a plug screwed 5 into the rear of the mounting and having an air connection and forming a joint with the air nozzle; and a packing at the rear end of the nozzle expanded by the pressure 10 between the plug and the mixture nozzle forming a closure in the screw-threaded opening.

4. In an atomizer, the combination of a mounting having a screw-threaded opening therethrough; a mixture jet nozzle screwed 15 into the opening and having a chamber at its rear with a fuel connection; an air nozzle extending into the chamber and having a shoulder at its end engaging the end of the mixture nozzle; a plug screwed into the 20 rear of the screw-threaded opening forming a joint with the air nozzle and having an air connection; and a packing between the end of the plug and the shoulder on the air nozzle.

5. In an atomizer, the combination of a mounting having a screw-threaded opening therethrough and a fuel passage therein; a mixture jet nozzle screwed into the opening having a chamber therein with a radial 30 opening leading therefrom and an annular groove to which the radial opening leads; an air nozzle extending into the chamber; and means for securing the air nozzle in place and connecting the same to an air 35 supply.

6. In an atomizer, the combination of a mounting having a screw-threaded opening therethrough and an air passage therein; a mixture jet nozzle screwed into the opening; an air nozzle leading into the mixture jet nozzle; a plug arranged in the rear of the screw-threaded opening, said plug having an opening communicating with the air nozzle and a radial opening leading from 45 the opening in the plug; and an annular groove communicating with the radial opening, said annular groove registering with the passage in the mounting.

7. In an atomizer, the combination of a 50 mounting having a screw-threaded opening therethrough, a fuel passage therein, and an

air passage therein; a mixture jet nozzle screwed into the opening and having a chamber at its rear from which leads a radial opening; an annular groove to which the radial opening leads communicating with the fuel passage; an air nozzle arranged in the chamber; and a plug securing the air nozzle and communicating therewith, the plug having a central opening, a radial opening leading therefrom and an annular groove leading to the radial opening, the annular groove communicating with the air passage in the mounting.

8. In an atomizer, the combination of a 65 mounting having a screw-threaded opening therethrough, a fuel passage therein, and an air passage therein; a mixture nozzle screwed into the screw-threaded opening, said nozzle having a chamber at its inner 70 end, a radial opening leading from the chamber, and an annular groove to which the radial opening leads, the annular groove communicating with the fuel passage; an air nozzle extending into the chamber and 75 having a shoulder at its rear; a plug at the rear of the screw-threaded opening and having an opening into which the air nozzle extends, radial openings leading from the opening in the plug, and an annular groove 80 on the plug to which the radial groove in the plug leads, said annular groove registering with the air passage; and a gasket between the end of the plug and the shoulder on the air nozzle.

9. In an atomizer, the combination of a mounting having a screw-threaded opening therethrough; a mixture jet nozzle screwed into the opening having a chamber at its rear with a fuel connection; an air nozzle 90 extending into the chamber; a plug screwed into the rear of the mounting and having an opening receiving the air nozzle and forming a joint therewith, said plug having an air connection leading to the nozzle; a screen in the opening in the plug over the end of the air nozzle; and a spring arranged in the opening in the plug and holding the screen in place.

In testimony whereof I have hereunto set my hand.

ROBERT F. METCALFE.
